METHOD OF COKING HYDROCARBON MATERIAL

Arthur J. Boynton, Winnetka, Ill., assignor to
 Brassert-Tidewater Development Corporation,
 Chicago, Ill., a corporation of Delaware

Application February 17, 1934, Serial No. 711,665

1 Claim. (CL 202—15)

This invention relates to a new and improved method for the coking of bituminous or asphaltic liquids, pitches, petroleum residues and other fluid or semi-fluid compounds which may or may not 5 contain entrained solid fuels.

It is to be understood that the invention relates to the treatment of materials of this character which are normally fluid or which may be rendered fluid by heat so as to be fluid under the 10 conditions of the treatment. It is to be further understood that the invention relates to treatment of materials which contain entrained solid matter such as carbon or the like, due to the nature of the materials themselves or to which 15 solid materials have been added, the liquid portions serving as a carrying medium for the solids.

Many attempts have been made to satisfactorily form coke in a chamber by heat interchange between hot vapors and the charge to be coked. 20 In many cases it has been found that the resultant coke is uneven in structure and also in percentage of volatile matter, due to the difficulty of satisfactorily equalizing the heat transfer through the mass. I have discovered that by feeding the charge into a coking chamber at a rate 25 which bears a definite relation to the heat brought into the chamber by the vapors and by properly distributing the vapor flow throughout the chamber, the heat exchange may be substantially 30 equalized throughout the area. The vapors are led across the upper surface of the coking mass so as to permit direct conduction of heat to the coking mass. In order to equalize this heat transfer the direction of flow and point of introduction 35 may be periodically reversed. The heating gases are preferably introduced along one side of the chamber and discharged from the other together with volatiles which are driven off from the charge being treated. The point of introduction is 40 preferably adjacent the highest point attained by the progressive building up of the coke layer and directed toward that layer, and its direction is preferably downward so that the velocity of the incoming gases will force them in contact with the 45 surface of the coking mass.

Duplicate ports will preferably be provided on opposite sides of the chamber and will serve alternately for introducing the gases and removing the volatile products of the process. In a preferred 50 method the charge is fed onto the floor by increments so that only a small amount is exposed to the heated gases at one time. In this way the coke layer is built up in steps and the volatile matter left in it can be more easily controlled. 55 There will be, therefore, no necessity for heat

transfer through any great thickness of the material.

It is an object of the present invention to provide a new and improved method for coking materials of the character described. 5

It is a further object to provide a method whereby the coking may be carried on without the application of external heat.

It is an additional object to provide a method in which the heat is applied by gaseous medium 10 directly to the coking surface.

It is also an object to provide a method whereby it is unnecessary to transmit the heat through any portion of previously coked material.

It is an additional object to provide a method 15 whereby the application of heat to the material being treated may be equalized over the area of such material.

Other and further objects will appear as the 20 description proceeds.

I have shown certain preferred embodiments of 25 my invention in the accompanying drawings, in which—

Figure 1 is a plan view of an oven according 25 to one form of construction;

Figure 2 is a horizontal section taken on line 2—2 of Figure 3;

Figure 3 is a vertical section taken on line 3—3 of Figure 2;

Figure 4 is a view similar to Figure 1 but showing a modified form of construction; 30

Figure 5 is a horizontal section taken on line 5—5 of Figure 6; and

Figure 6 is a transverse vertical section taken 35 on line 6—6 of Figure 4.

Referring first to the form of construction shown in Figures 1, 2 and 3, the horizontal metallic shell 11 is supported on a base 12 and contains a refractory lining 13 which forms a coking chamber 14 having a flat floor 15 and an arched roof 40 16. The ends of the chamber are closed by removable doors 17. A platform 18 is shown at each end of the oven for use in pushing coke out of the oven. The upper portion of the oven is provided with the intake 19 connected to header 20, which 45 serves for the introduction of the hydrocarbon material being treated. A burn-out relief passage 21 is located in the top of the chamber.

The left side of the chamber, as seen in Figure 3, is provided with a series of nozzles or tuyères 50 22 which are connected with a header 23 and serve for the introduction of the gases or vapors which serve to carry the heat into the coking operation. The opposite side of the oven is provided with a series of ports 24 connected to head- 55

er 25, which serve to withdraw the hot heat carrying medium together with any volatiles swept out of the material being treated.

The form of construction shown in Figures 4, 5 and 6 includes a steel shell 30 which is shown as being oval in cross section. It contains the refractory lining 31 forming the chamber 32 having a flat floor 33 and an arched roof 34. The heating passages 35 are located below the floor 33 and may be fed with fuel for combustion through nozzles 26. These passages 35 communicate with longitudinal flue 36 which in turn communicates with the offtake flues 37. The header 38, which serves for the introduction of the heating medium, is connected through valve 39 to a cross header T 40. Valves 41 and 42 are provided on either side of the T and connect into the header branches 43 and 44. These headers 43 and 44 join the offtake T 45 through valves 46 and 47. The T 45 leads through passage 48 to offtake passage 49 which is shown as connected to a bubble tower or fractionating apparatus 50.

The header 43 is provided with a plurality of ports 51 which discharge downwardly into the chamber 32 in a line directed toward the floor thereof or toward the layer of coke forming on the floor. The header 44 is similarly provided with a plurality of ports 52 communicating with the chamber 32. This form of oven is provided with a pipe 53 which serves to introduce the material being treated through the pipe 54 directed into the top of the chamber. This pipe 54 is controlled by valve 55. The chamber is also provided with a burn-out or blow-off discharge passage 56. The ends of the oven are closed by removable doors 57 and 58.

In the operation of the form of oven shown in Figures 1 to 3, the material to be treated, which as has been stated, is in fluent form, is deposited through passage 19 onto the floor of the chamber. In starting up the process, however, the gases which serve to heat the chamber will first be introduced for a period through ports 22 so as to heat up the chamber and bring the refractory floor and lining up to substantially coking temperature. The flow of material to be treated is then started and this material spreads out in a relatively thin layer on the flat floor and gradually builds up. As it builds up it is reduced to coke by heat transmitted from the non-oxidizing gases introduced through the ports or nozzles 22. The flow of gas and of the material to be treated will be preferably so related that the coking takes place at substantially the same rate as the input of material. The gases, after they have given off their heat, are drawn off through ports 24 and header 25 carrying with them the volatiles liberated from the material being treated. After the desired thickness of coke has been formed, the flow of material to be treated is cut off

through pipe 19. The flow of gases may be continued for a period so as to fully coke the last material to be deposited. The flow of gases is then stopped and the chamber may be steamed out, after which the end doors may be opened and the formed layer of coke forced out by means of mechanical pushing or pulling apparatus.

The form of construction of Figures 4, 5 and 6 is operated in much the same manner. In this form of construction, however, the floor of the oven may be heated by external application of heat through the flues 36. This heating may take place intermittently or throughout the process, as desired. In one method of operating the flues would be used merely to heat up the oven before starting. In another method the flues may be used during the initial treatment of each successive charge and heat partly or entirely cut off after the charge builds up to substantial thickness, so that it acts as a heat insulator. The main portion of the heat for the coking operation, however, is preferably supplied by gases which are introduced through either the series of ports 51 or the series 25 of ports 52. It will be understood that with valves 41 and 47 closed, and valve 39 open, the hot gases used as the heating medium will follow the arrows in Figures 4 and 5 and be discharged into the coking chamber through the ports 51. 30 These gases will impinge on the floor or on the coke layer thereon and will pass across the oven and out through the ports 52 where they will follow the arrows through header 44, valve 46 and offtake passages 48 and 49 to the treatment 35 chamber 50. By closing valves 42 and 46 and opening valves 41 and 47 the direction of flow of the gases across the chamber will be reversed. An intermittent reversal of flow during the process serves to equalize the heat supplied to various portions of the layers so as to give a more uniform thickness and quality of coke on different parts of the floor. Coke will be removed from the oven of this form of construction in the same manner as that described in connection with 45 Figures 1, 2 and 3.

It will be understood that these forms of construction are merely illustrative and that I contemplate such further changes and modifications as come within the spirit and scope of my invention.

I claim:

The method of coking hydrocarbon material in fluent form, which comprises progressively depositing a layer of such materials in a closed 55 chamber, passing over and in contact with the upper surface of said layer as it is formed a highly heated non-oxidizing gaseous medium, and periodically reversing the direction of flow of said gaseous medium.

ARTHUR J. BOYNTON.
